UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,270,752.

Specification of Letters Patent. Patented June 25, 1918.

Application filed June 25, 1913. Serial No. 775,621.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

10 My invention relates to computing machines, and is disclosed as applied to a computing machine of the Underwood-Wright type.

In my application No. 753,254, filed March 15, 1913, is disclosed a power-driven mechanism controlled by the numeral keys of the typewriter and operating a master wheel, which turns *serializm* the computing wheels of a totalizer. The computing mechanism 20 comprises a wheel whereon are index pins settable concomitantly with the operation of the numeral keys of the typewriter.

Each key selects an index pin and releases a trip shaft, which shaft locks the typewriter carriage against movement. At the 25 same time an electric circuit is closed, starting the motor. The trip shaft causes said motor to set that index pin which has just been selected by the key operated; and the motor then goes on to turn the master wheel to a corresponding extent, whereby 30 the number is registered in the totalizer.

A totalizer carriage is also shown in said application, which is manually connectible 35 to the typewriter carriage, so that the two move together; and means are also shown in said application for locking the computing carriage against travel while the computing mechanism is in motion, and thereby 40 locking the typewriting machine carriage against motion.

Each computing wheel is shown in said application as normally held alined by a spring detent, as is usual in totalizers of the 45 Underwood-Wright type.

According to one feature of the present invention, the detent of the active computing wheel may be moved to ineffective position before the master wheel turns, thus re-

ducing the noise and wear incident to turning a toothed wheel against the opposition of the detent.

Said detent may include an arm which forms part of a lock for directly holding the computing machine carriage against stirring while the master wheel is turning. This lock is preferably so built that it is strong enough to overcome any tendency of the typewriter carriage to incorrectly position the computing machine carriage, and therefore it positively alines the computing machine carriage.

Another feature of the present invention is to render the mechanism so compact that the totalizer may be at the front of the typewriter and near to the printing point in a visible writing machine, while at the same time the totalizer may be so formed that it only slightly overhangs the typewriter keyboard, and so does not handicap the operator in using the machine. For this purpose the totalizer carriage may be supported on the usual front bar of the Underwood typewriting machine and the totalizer itself may be so mounted on said carriage that the numeral wheels lie at the foremost upper corner of said totalizer, thus bringing them to a convenient point for the operator to read, while at the same time the master wheel is adjacent said front bar, where it is less likely to be accidentally struck. The carry-over mechanism may be beneath the master wheel and formed of small wheels, thus allowing the front of the totalizer to be cut away sharply from the sight opening, through which the dial wheels are read. The totalizers are more conveniently attached to the carriage than heretofore.

Other features and advantages will hereinafter appear.

In the accompanying drawings, Figure 1 is a front view of an Underwood-Wright combined typewriting and computing machine, showing so much thereof as is necessary to the understanding of my invention.

Fig. 2 is a similar part sectional side view of the same.

Fig. 3 is a perspective view showing details of the computing machine carriage and some adjacent parts.

Fig. 4 is an end view of Fig. 3.

5 Fig. 5 is a perspective view, largely broken away, of many of the parts seen in Fig. 1.

Fig. 6 is an end view partly cut away of part of Fig. 5.

10 Fig. 7 is a sectional view of the left-hand end of Fig. 5.

Fig. 8 is a front view of a totalizer partly cut away.

Fig. 9 is a perspective view of a detail of 15 the carry-over mechanism.

Fig. 10 is a plan view of the connections between the computing and typewriter carriages.

Fig. 11 is a plan view of another form of 20 totalizer with the top cover removed.

Numeral keys 1 and alphabet keys 2 of the Underwood typewriting machine are mounted in the frame 3 in any usual or desired manner, and as described in my application 25 753,254, filed March 10, 1913, each numeral key when operated releases the trip shaft 4, so as to cause the computing mechanism to rotate the master wheel drive shaft 5 to an extent determined by the key depressed, thereby causing the master wheel 6 (see 30 Fig. 8) to rotate the computing wheel 7 with which it is at the moment engaged.

The computing wheels 7 form a gang which are constantly in mesh with dial 35 wheels 8. Said dial wheels bear on their outer periphery digits 9, and are rotatable to cause their digits to appear before the sight hole 10 of a totalizer 11. As herein disclosed said totalizer forms part of a com-

40 puting machine carriage, which moves concomitantly with the typewriter carriage, so as to bring its computing wheels 7 *seriatim* into engagement with the master wheel 6, said master wheel (as best seen in Fig. 8) 45 having external teeth 12 which mesh with internal teeth 13 on the computing wheels, there being as usual ten teeth 13 where the computing mechanism is used to register numbers in the decimal system.

50 The typewriter carriage 14 (see Figs. 2 and 7) is supported on rolls 15 which travel in a track 16 on the front bar of the typewriting machine. Said carriage is fed along in any desired or usual manner by means of 55 a universal bar (not shown) which is operated at every depression of a type key. Said carriage includes the usual platen, not shown, whereon numbers and letters are written, and said carriage carries along the 60 computing machine carriage with it by means of an arm 17 pivoted to an extension 18 of the typewriter carriage frame, on which arm is fast a double dog or stop 19, which stop when thrown down forwardly en-

ters between the teeth of a rack bar 20 fast 65 on the computing machine carriage; thus when the typewriter carriage travels along, it carries with it the computing machine carriage and the totalizers 11 mounted on said carriage.

70 The computing machine carriage includes an E-shaped frame bar 21, and in a depression in said frame bar is mounted a rack bar 22 having openings therein at letter-space intervals, said rack bar being adapted to hold in position the totalizers 11 by means of locking dogs 23, each dog having an oblong enlarged end which enters into an elongated opening 22^b. When the dog has been inserted and turned across the opening 22^b 80 by means of a handle 24, the enlarged end may be drawn up tight against the lower face of the rack bar, against the tension of a spring 22^a, thus locking the totalizer.

85 Each dog 23 is mounted on an extension 25 of its totalizer 11, which extension overlies the upper flat surface 26 of the frame bar 21 on each side of the rack bar 22. The extension 25 includes a tongue 25^a which enters between the surfaces 26 and alines the 90 totalizer 11 with the computing machine carriage.

95 The computing machine carriage is supported by roller bearings 27 on the usual front bar of the typewriting machine. For this purpose there is mounted on said front bar a track bar 28 having in the front thereof an inverted horizontal track 29, and a vertical track 30, while at the rear are two inclined tracks 31 and 32 set at right angles 100 to each other, but inclined so that one of them lies nearly parallel to the top of the ordinary front bar of the typewriter.

105 The computing carriage 21 includes on its internal surface tracks opposing these tracks, and between the corresponding sets of tracks are interposed rollers 86 joined together by frames in pairs so that two adjacent rollers have their axes at right angles to each other, and the pairs are joined together by a rod 110 34 thus making a frame which serves as a space guide for the rollers. This roller bearing insures that the computing carriage shall travel easily and that the thrusts on the computing machine carriage shall be received on adequate surfaces.

115 The computing machine carriage, as shown in Fig. 1, may be of sufficient length to accommodate several totalizers 11, and the rack bar 20 is properly alined therein by means of the threaded ends of brazed extensions 35, which extensions pass through outer plates 36 and carry on their outer ends nuts 37, which may be tightened against said end plates.

120 The rack bar 20 on the computing machine carriage is set to one side of the center thereof, and the dog 19 on the typewriter

carriage is correspondingly to one side, thus allowing the operator to have an unobstructed view of the pointer 38 on the typewriter carriage and the scale bar 39, by which said pointer indicates the printing position of the typewriter carriage.

In a totalizer of the usual Underwood-Wright type, whenever a dial wheel turns to bring its zero to the sight opening 10, it turns the computing wheel meshing therewith, so that a broad tooth 40 on said computing wheel gives a gear 41 forming part of a carry-over wheel a slight turn, thus bringing a group of interrupted teeth 42 on said carry-over wheel to where they will be struck by a power-driven roll or gear 43. Said power-driven roll will complete the turning of said carry-over wheel an aliquot portion of a revolution. In so turning the carry-over wheel, the adjacent computing wheel of the higher denomination is turned by gear 43 forming another integral part of said carry-over wheel, said gear constantly meshing with the external teeth 44 on said adjacent computing wheel, said teeth 44 being the teeth with which said computing wheel meshes with its dial wheel 8. Thus every time a dial wheel turns to bring its zero wheel to a sight opening, it turns the adjacent dial wheel one unit space, making a carry-over. To prevent the carry-over wheel from being overthrown by the power-driven wheel 43, a detent roll 45 is journaled on an arm 46, so that a spring 47 normally presses the detent roll 45 into a rounded-cut space between two groups of the teeth of the gear 41. Since each carry-over wheel is constantly in mesh with the computing wheel next higher in denomination and said computing wheel is constantly in mesh with its own dial wheel, these detent rolls 45 hold the dial wheels aways alined.

Means are provided whereby, whenever a numeral key is depressed, the detent roll 45, holding the computing wheel at the moment engaged by the master wheel, is carried clear of its carry-over wheel, so that said computing wheel may be freely turned by the master wheel without the noise and wear incident to turning a wheel held by a detent. This release is brought about by the trip shaft 4 which is allowed to rotate every time a numeral key is operated, thus permitting a strong spring 64 to carry upwardly a control bar 50. Said control bar has pivoted at its upper end a link 51, which link whenever the control bar rises, by means of a rock arm 52, swings a rock shaft 53 so that a rock arm 54 fast on said shaft will project a plunger 55 against an extension 56 of the detent roll arm 46 to move said arm outward. This plunger 55 is pointed and made of hardened steel, and is practically alined with a master wheel 6, so that it swings and

makes ineffective the detent roll 45 which holds the computing wheel which the master wheel is about to turn, and in so doing, carries the extension 56 of the detent arm 46 into a lug 57 on the typewriter frame. Said lug is recessed at 58, the sides of said recess forming a sharp V which coöperates with the correspondingly V-shaped sides 59 of the extension 56 and fits them closely. When the plunger 55 has thus moved a detent bar extension 58 into the lug 57, said extension 58 positively holds the totalizer 11 against movement. After this has been done the master wheel is connected to the power by the trip shaft 4, and then may be rotated. To make this holding positive, said extension 56 is arranged to engage the lug 57 over a considerable portion of its length, so that the V-shaped sides will get a firm hold on each other. Furthermore, lost motion is prevented by having the upper ends of the detent bars 46, as seen in Fig. 8, closely fitting against each other, and the end bars bear against collars 59 fast on a shaft 60, fast in the sides 61 of the totalizer.

The plunger 55 slides in guides 62 fast on the frame of the typewriting machine, and the rock arm 54 moves the plunger 55 back and forth in said guides by means of a pin 63 fast on the plunger, which pin is engaged by said rock arm. The spring 64 is of such strength that it will positively aline the proper computing wheel with the master wheel, being strong enough to overcome the ordinary spring (not shown) which drives the typewriter carriage. Moreover, the V sides center the computing carriage if it is not exactly alined in its proper position of rest. The pin 63 is so mounted on the plunger 55 that a slight overthrow of the plunger 55 will bring said pin against the forward guide 62, and thus prevent the spring 64 from materially overthrowing the control bar 50, if the extension 56 should break off.

In order to give further rigidity to the rock shaft 53, said shaft is carried in journals 65 near the rock arm 54 thereon, and is also journaled in the side plate 66 of the computing machine near the rock arm 52 thereon.

The master wheel 6 is nearly in the plane of the printing point and is carried on a long steel shaft 67 which is journaled at one end only on the side plate 66 in a long bearing 68 fast on said plate, thus the spring of said shaft gives some play so as to allow the master wheel to enter a totalizer if there should be any sag in the machine. To insure the master wheel's thus entering, the wheel includes a hub 69 which is nearly of the size of the internal teeth 13 of the computing wheels, and said hub is beveled off at 70 at each end, so that in effect the ends

of said hub form cams which will coöperate with the hubs of the end computing wheels; and if the master wheel shaft is not properly aligned will cam the master wheel into the proper position. Since the master-wheel shaft is journaled at one end only, it is unnecessary to dismantle the bearings of said shaft to attach an additional totalizer or remove any totalizer, this being so because the totalizers are entirely free of the master-wheel shaft when the computing carriage is at the left end of its travel. Said master wheel, as is usual in the Underwood-Wright machine, is driven by a bevel gear 72 meshing with two loose bevel gears 73, 74, running loose on the master wheel drive shaft 5, but adapted to be clutched thereto in the usual manner by a clutch 75. By shifting said clutch, said master wheel may be caused to either add or subtract, since when the clutch engages with one gear, it turns the master wheel in one direction, and when engaged with the other gear, it turns the master wheel in the opposite direction.

25 The power-driven carry-over assisting wheel 43 is driven from the same source of power as the master wheel shaft 67 by means of a drive shaft 76 having a clutch 77 which is adapted to be shifted simultaneously with the clutch 75, by means not shown, thus reversing said assisting wheel whenever the master wheel is reversed.

30 Bevel gears 78 driven by the shaft 76 mesh with a bevel gear 79 which, through gears 80 and 81, drives a shaft 82 to which said carry-over assisting wheel is fast. Said shaft 82 turns in a fixed journal 83 in the plate 66, but is journaled in the usual resilient journals 84 adjacent the master wheel, so that, if said assisting wheel fails to mesh properly with any carry-over wheel 48, its long shaft will permit it to spring clear of said wheel momentarily, and later in its turning it may mesh properly with said wheel.

35 The master wheel 6, as has been stated, is preferably located just about in the plane of the typewriter printing point, and the lug 57 against which the computing carriage is locked is located almost in a line with said master wheel, being slightly offset therefrom, as seen in Fig. 8, to allow for the fact that the carry-over wheel of each computing wheel is offset somewhat therefrom. It will 40 also be seen in said Fig. 8 that the detent rolls 45 are carried in central slots 85 in the detent bars 46.

45 The roller bearings 27 on which the computing machine is carried include rolls 86 which, as has been stated, are set at right angles to each other, each roll having a pivot at each end, which pivot passes through an ear 87 at each side, and is headed over said ear. Said ears are made by bend-

50 ing tongues projecting from a flat strip of metal at right angles to said metal, so that two tongues form a channel 88, as seen in Fig. 1, within which the rolls 86 turn while the other pair of tongues are bent in the opposite direction forming a channel at 55 right angles to the first channel 88. One pair of ears or tongues 87 is extended at 89 to form members which lie on each side of the bar 34, and said extensions are riveted to said bar. A similar roller bearing, as has been stated above, is riveted to the other end of said bar.

55 The arm 17 by which the typewriter carriage carries along the computing machine carriage, is shown in plan view at Fig. 10, 60 where it will be seen that the hinge 18 which carries it is adjustably mounted on the typewriter carriage by screws 90, which pass through slots 91 of the plate 92 which forms the hinge, and the arm 17 is normally 65 thrown forward against the rack 20 by means of a spring 93 coiled around the axle of the hinge, and lying between the arms 94 which form part of the arms 17.

60 As is best seen in Figs. 7 and 11 the numeral wheels 8 occupy the very front of the totalizer, and behind these wheels lie the computing wheels, which are placed near the rear wall of the totalizer. This allows the totalizer to be kept from overhanging the 65 keyboard of the typewriter enough to interfere with the convenient operation of the typewriter. This brings the carry-over wheels at the rear of the totalizer, and the detent arms 46 may be pivoted beneath and 70 behind the dial wheels, whence they extend rearwardly and down to the lug 57. The front wall 96 of the totalizer, as best seen in Fig. 7, slants backward rapidly from the dial wheels, thus, as will be seen from Fig. 105 2, still further reducing the tendency of the totalizer, to obscure the typewriter keyboard. By having the computing wheels at the very rear of the totalizer, the master wheel shaft is brought close to the front bar of the typewriter, in which place it is largely protected 110 from injury by said bar, and at the same time this enables the mechanism on the end plate 66 to be made very compact. The advantage of having the front of the totalizer slope 115 downwardly and rearwardly is especially apparent when it is remembered that the operator always sits at some distance in front of the machine, and so sees the keyboard from quite an angle. Since the flat bottom of the 120 totalizer extends only a little farther forward than the numeral key 1, it will be evident that the totalizer will in no way interfere with a clear view of the numeral keys, which as usual occupy the top bank of the 125 keyboard.

120 In Fig. 11, it will be noted that the numerals read downwardly and that the dial wheels

have the gears by which they are driven at the right-hand sides, while the computing wheels have their gears at their right-hand sides mesh with the corresponding dial 5 wheels. In the form of totalizer shown in Fig. 11, comma and decimal spaces are left, formed by a plurality of double washers 95, which embrace a rod or tube 96 on which the dial wheels 8 are journaled and which also 10 extend between the computing wheels 7. As has been stated, in said totalizer each computing wheel is constantly in mesh with a carry-over wheel and also constantly in mesh with a dial wheel. Each carry-over wheel 15 which carries over across the washers 95 is formed with a long barrel as usual in the Underwood-Wright computing machines. The washers 95 are kept in place by the rod 96 which passes through the washers be- 20 tween the dial and computing wheels.

The computing wheels are supported by the carry-over wheels and the dial wheels with which they mesh; said carry-over wheels being journaled on a fixed shaft 101. 25 Each computing wheel is held in place to engage its dial and carry-over wheel by a plate 97, which is carried by rods 98, 98 at the top of the totalizer, each plate 97 having a semicircle cut in it which forms a journal 30 bearing for the shoulder 99 of its computing wheel. The dial wheels and computing wheels are spaced from the walls of the totalizer casing by suitable washers 100.

It will be observed from Fig. 1, that the 35 roller bearings of the totalizer carriage are so placed that the rolls support said carriage on each side of the master wheel.

Variations may be resorted to within the scope of the invention, and portions of the 40 improvements may be used without others.

Having thus described my invention, I claim:

1. In a combined typewriting and computing machine, the combination with a typewriter carriage, of a computing machine carriage traveling concomitantly therewith, a totalizer on said computing carriage, a lug comprising V-shaped sides fast on the frame of the machine, a separately operable locking bar on said totalizer for each denomination in which computing may be done in said totalizer, said bars each having sides adapted to fit said lug closely, and means for moving said bars one at a time against said lug 50 to firmly hold the computing machine carriage in place before the computing operation begins.

2. In a combined typewriting and computing machine, the combination with a typewriter carriage and a computing machine carriage, of a V-shaped locking bar at every space on said computing machine carriage in which computing is likely to be done, a lug comprising V-shaped sides on

the frame of the machine, guides on the 65 frame of the machine, and a plunger traveling in said guides to carry said locking members to closely engage said lug and positively center the computing machine carriage during the computing operation. 70

3. In a combined typewriting and computing machine, the combination with numeral keys and a traveling carriage, of a frame on which said carriage travels, computing wheels, a master wheel arranged to 75 engage said computing wheels *seriatim* as determined by said traveling carriage, a detent for each computing wheel, a bar forming an extension of each detent, a co-operating locking member common to said detents, 80 and means for swinging the detent adjacent the master wheel to carry it clear of its computing wheel and carry its bar into locking engagement with said locking member to lock the carriage. 85

4. In a combined typewriting and computing machine, the combination with numeral keys and computing wheels, of a computing machine carriage in which said computing wheels are mounted, a detent for each computing wheel normally holding it, an extension of each detent forming a locking member, a co-operating locking member common to said detents and fast on the frame of the combined machine, a master wheel for rotating 90 said computing wheels *seriatim* to an extent determined by the numeral keys depressed, and means under the control of said numeral keys for operating said detents to carry them clear of their computing wheels 100 and carry them to locking position before said master wheel turns the computing wheel with which it engages.

5. In a combined typewriting and computing machine, the combination with numeral keys and computing wheels, of a computing machine carriage in which said computing wheels are mounted, a detent for each computing wheel normally holding it, an extension of each detent forming a locking member, a co-operating locking member fast on the frame of the combined machine, a master wheel for rotating said computing wheels *seriatim* to an extent determined by the numeral keys depressed, a plunger on the 110 frame of the machine adjacent said co-operating locking member, and means under the control of the numeral keys for causing said plunger to move a detent into locking position before the master wheel turns the computing wheel with which it engages. 115

6. In a combined typewriting and computing machine, the combination with numeral keys and computing wheels, of a computing machine carriage in which said computing 125 wheels are mounted, a detent for each computing wheel normally holding it, an extension of each detent forming a locking member, a co-

operating locking member fast on the frame of the combined machine, a master wheel for rotating said computing wheels *seriatim* to an extent determined by the numeral keys depressed, a control bar, means operated by said control bar for causing a detent extension to lock the computing machine carriage, and a trip shaft under the control of said control bar for later causing the computing mechanism to carry into the computing wheels the number represented by the keys struck.

7. In a combined typewriting and computing machine, the combination with numeral keys and computing wheels, of a computing machine carriage in which said computing wheels are mounted, a detent for each computing wheel normally holding it, an extension of each detent forming a locking member, a coöperating locking member fast on the frame of the combined machine, a master wheel for rotating said computing wheels *seriatim* to an extent determined by the numeral keys depressed, a control bar, means under the control of said bar for carrying a detent extension into locking engagement with said coöperating locking member, a spring normally tending to force said locking member into place, said spring strong enough to overcome any other driving means for the computing machine carriage, means for operating said control bar by the numeral keys, and means whereby the control bar later causes the turning of the master wheel.

8. In a combined typewriting and computing machine, the combination with numeral keys, of a traveling carriage, means for driving said traveling carriage, a spring-operated locking member more powerful than said driving means for locking said carriage against traveling, and means made effective by the operation of each numeral key for moving said locking member to effective position before the computing machine is operated by the numeral key.

9. In a combined typewriting and computing machine, the combination with a traveling carriage and means for driving it, of numeral keys for determining how the wheels forming part of said computing machine shall turn, a combined locking and alining member for bringing the carriage to proper position and locking it before any computing wheel is so turned, and power operated means for operating said lock more powerful than the means for driving said carriage.

10. In a combined typewriting and computing machine, the combination with numeral keys, a master wheel and a traveling carriage, of computing wheels forming part of said traveling carriage, a detent for each computing wheel, a locking extension of

each detent, a coöperating lock on the frame of the machine, and means for moving the detent of the computing wheel which the master wheel engages, so that the locking extension engages with the coöperating lock.

11. In a combined typewriting and computing machine, the combination with a traveling carriage comprising computing wheels and carry-over wheels, of a master wheel for turning said computing wheels *seriatim*, a carry-over assisting roll for assisting the carry-over wheels above the master wheel to turn their computing wheels, resilient journals in which said assisting roll is mounted adjacent said master wheel, a fixed journal at a distance from said resilient journals, and a resilient shaft for said carry-over roll journaled in said fixed journal and said resilient journals.

12. In a computing machine, the combination with computing wheels, numeral keys and a traveling carriage, of an escapement device for feeding said carriage along, computing wheels in said carriage, a detent for each computing wheel, a locking member on the frame of the machine, means associated with each detent coöperating with said locking member to lock said carriage, and a plunger adapted to free the computing wheel from its detent and to lock said carriage by said locking member whenever a numeral key is operated.

13. In a combined typewriting and computing machine, the combination with a letter-feeding typewriter carriage and a computing machine carriage, of computing wheels forming part of said computing machine carriage, a master wheel adapted to turn said computing wheels *seriatim* as determined by said letter-feeding carriage, a detent for each computing wheel comprising a swinging bar, a locking member on the frame of the machine, an extension of each detent bar adapted to coöperate with said locking member, and means forming part of said locking member for positively moving the computing machine carriage by the engaging detent bar to align its computing wheel with the master wheel if the letter-feeding carriage has incorrectly arrested it.

14. In a computing machine, the combination with dial wheels and carry-over wheels, of detents effective on said dial wheels but operating through the carry-over wheels, an extension of each detent, a computing carriage, and a locking lug adapted to be engaged with any one of said extensions to hold said carriage against movement when any detent is carried clear of its carry-over wheel.

15. In a computing machine, the combination with a traveling carriage and a series of detents, of extensions of said detents, a plunger for locking said carriage against

travel, and a lug coöperating with said extensions to make said lock effective.

16. In a computing machine, the combination with a traveling carriage, of a locking device for said traveling carriage, normally locked computing wheels, numeral keys controlling said wheels, a source of power independent of said keys for unlocking said computing wheels by the operation 5 of said locking device, and means operated by said source of power for simultaneously making said carriage-locking device effective.

17. The combination with a front-strike 15 typewriting machine having a traveling carriage and a transverse front bar some distance in front of the printing point, of a computing carriage slideable along said front bar, a main bar forming part of said computing carriage and channeled to partly embrace said front bar, a totalizer adapted to be attached to said main bar, and a coöperating tongue and groove for alining said totalizer on said main bar.

25 18. The combination with a front-strike typewriting machine having a traveling carriage and a transverse front bar some distance in front of the printing point, of a computing carriage slideable along said front 30 bar, a main bar forming part of said computing carriage and channeled to partly embrace said front bar, a totalizer adapted to be attached to said main bar, a groove in said main bar, a tongue fast on said totalizer 35 and adapted to coöperate with said groove to aline said totalizer, and means effective in said groove for attaching said totalizer in place in said groove.

19. The combination with a front-strike 40 typewriting machine having a traveling carriage and a transverse front bar some distance in front of the printing point, of a computing carriage slideable along said front bar, a main bar forming part of said computing carriage and channeled to partly embrace said front bar, a totalizer adapted to be attached to said main bar, roller bearings forming the sole support of the computing carriage interposed between said main bar 45 and said front bar, a master wheel for operating said totalizer, and means independent of said bars for steadyng said totalizer while it is being operated.

20. In a combined typewriting and computing machine, the combination with a typewriter carriage, and a computing machine carriage having a considerable range of movement and comprising computing wheels, of a master wheel internal to said 55 computing wheels, said master wheel and computing wheels having a relative lateral movement, and a long resilient shaft carrying said master wheel, said shaft journaled, during the limit of movement of said com-

puting carriage, at one end only of the machine, and having a bevel surface thereon adapted to guide said shaft into engagement with the computing wheels during said lateral movement.

21. In a computing machine, the combination with a traveling carriage, of computing wheels, actuating means for engaging said wheels *seriatim* under the control of said carriage, detents for said wheels normally restraining their too free operation, 70 means for moving said detents one at a time from engagement with said wheels as the wheels are operated *seriatim*, and means enabling said detents, on moving from a position to release said wheels, to lock said 80 carriage.

22. In a combined typewriting and computing machine, the combination with a typewriter carriage, and a computing machine carriage having a considerable range 85 of movement and comprising dial wheels, of a master wheel having relative movement with respect to said dial wheels, external teeth on said master wheel, wheels adapted to turn said dial wheels comprising internal 90 teeth, a long resilient shaft on which said master wheel is fast, and a journal for said master-wheel shaft at one end only, said journal permitting said shaft to swing to fit said internal teeth, and said shaft having a 95 bevel thereon for causing it to swing to fit said internal teeth.

23. In a combined typewriting and computing machine, the combination with a typewriter carriage, and a computing machine carriage having a considerable range 100 of movement and comprising dial wheels, of a master wheel having relative movement with respect to said dial wheels, external teeth on said master wheel, wheels adapted 105 to turn said dial wheels comprising internal teeth, a long resilient shaft on which said master wheel is fast, a journal for said master-wheel shaft at one end only, said journal permitting said shaft to swing to fit 110 said internal teeth, said shaft having a bevel thereon for causing it to swing to fit said internal teeth, and detents holding said dial wheels alined, so that said master-wheel teeth will always mesh with said internal 115 teeth.

24. In a combined typewriting and computing machine, the combination with a traveling carriage, of a keyboard for said typewriting machine, and a totalizer 120 mounted on said carriage forward of the printing point, said totalizer having a casing provided with a flat top, so as to afford an unobstructed view of the printing point of the typewriter, and an inwardly slanting 125 front wall, so as not to interfere with the operator's hands in manipulating the keyboard.

25. In a combined typewriting and computing machine, the combination with a traveling carriage, of a keyboard for the typewriting machine, a totalizer mounted on said carriage forward of the printing point, dial wheels on said totalizer arranged at the upper front portion thereof, driving and carry-over wheels behind said dial wheels, and a casing for said totalizer having a flat top and a rearwardly slanting front face, whereby said totalizer enables a clear view of the printing point of the typewriting machine, and the ready manipulation of the keyboard thereof.
- 10 26. In a computing machine, the combination with a traveling carriage, of a totalizer on said carriage, a master wheel for said totalizer, a long resilient shaft carrying said master wheel, and a journal for said shaft at one end only, to permit it to swing to adapt itself to said totalizer.
- 15 27. In a computing machine, the combina-

tion with a totalizer comprising a series of computing wheels, of carry-over devices therefor, a carry-over assisting roll for said devices, a long resilient shaft for said assisting roll to permit it to swing to adapt itself to said totalizer, said shaft having a fixed bearing at the end remote from said assisting roll, and a resilient journal for said roll holding it adjacent the computing wheels on which it is effective.

28. The combination with a totalizer and a master wheel traveling relatively thereto, of a drive shaft for said master wheel of a length at least equal to the distance of relative travel between said totalizer and master wheel, and means for supporting said shaft at one end only, the master wheel being carried by the unsupported end.
